(57) **CLAIM**

The ornamental design for a shoe, as shown and described.

DESCRIPTION

FIG. 1 is a front perspective view of an embodiment of a shoe, it being understood that there is no claim being made to the bottom features, other than those visible in the views of the drawing disclosure for this embodiment, therefore the bottom view of this embodiment has been omitted.

FIG. 2 is a rear perspective view of the shoe of FIG. 1.

FIG. 3 is a right side view of the shoe of FIG. 1.

FIG. 4 is a left side view of the shoe of FIG. 1.

FIG. 5 is a rear view of the shoe of FIG. 1; and,
FIG. 6 is an enlarged view of the encircled area of a rear side of a midsole of the shoe seen in FIG. 5.

The dash-dot rectangle located around a portion of the claimed area of the rear side of the midsole in FIG. 5 is included to indicate an enlarged view of the claimed area of the rear side of the midsole only and forms no part of the claimed design.

The stippled surface shading in the enlarged view of the claimed area of the rear side of the midsole in FIG. 6 represents a three-dimensional appearance of the entire claimed area of the rear side of the midsole in FIG. 5. The stippled surface shading of the entire claimed area of the rear side of the midsole was omitted from FIG. 5 for clarity of illustration. The remainder of the shoe shown in broken lines is for environmental purposes only and forms no part of the claimed design.

1 Claim, 3 Drawing Sheets
